OSCAR C. RIXSON, OF NEW ROCHELLE, NEW YORK.

CREMORNE BOLT.

1,269,311.

Specification of Letters Patent. Patented June 11, 1918.

Application filed October 23, 1917. Serial No. 198,011.

To all whom it may concern:

Be it known that I, OSCAR C. RIXSON, a citizen of the United States, residing at New Rochelle, in the county of Westchester and State of New York, have invented certain new and useful Improvements in Cremorne Bolts, of which the following is a full, clear, and exact description.

This invention relates to Cremorne bolts adapted for use with swinging closures such as casements, doors and the like.

One of the objects of the invention is to provide a Cremorne bolt which is adapted to be attached to windows or other swinging closures having the portions thereof to which the bolt is attached of relatively narrow width.

Another object of the invention is to provide a Cremorne bolt having its bolt rods and guides so constructed that the bolt rods may be highly finished without liability of the finished surface becoming scratched or otherwise marked.

A further object of the invention is to provide a Cremorne bolt in which the guides which maintain the sliding bolt rods in position are entirely concealed from view and yet the bolt rods are securely held from rattling or otherwise becoming displaced.

A further object of the invention is to provide a Cremorne bolt which is interchangeable, that is, may have its handle arranged for rotation in the righthand or lefthand direction.

With these and other objects in view, which will be apparent from the detailed description hereinafter to follow, the invention consists of the constructions and combinations of parts which are set forth in the appended claims.

In the drawings:

Figure 1 shows a portion of the door or casement equipped with a Cremorne bolt constructed in accordance with the principles of the invention;

Fig. 2 is a plan of the bolt actuating mechanism, the casing being partially removed to more clearly show the parts;

Fig. 3 is a central vertical section through the mechanism disclosed in Fig. 2;

Fig. 4 is a view similar to Fig. 2, the connecting links being shown in reverse position;

Fig. 5 is a view similar to Fig. 2, showing

the position of the links when the bolt rods are retracted;

Fig. 6 is a vertical section through a portion of the bolt rod, showing the guide in position therein;

Fig. 7 is a view showing the guide in elevation;

Fig. 8 is a transverse section through the bolt rod and guide;

Fig. 9 is a detail showing the stud and the end of the bolt rod;

Fig. 10 is a detail of a modified construction, in which the actuating mechanism is operable by handles upon both sides of the swinging closure.

The Cremorne bolt constituting this invention is adapted to be utilized with swinging closures, such as doors and casement windows, with which Cremorne bolts are ordinarily used, and in Fig. 1 a section of the casement or window is shown consisting of two sections 1 and 2, one section having a stile or astragal 3 forming a part of its sash 4. A portion of the window frame is shown and designated 5. The Cremorne bolt which is mounted upon the stile or astragal 3 comprises two sliding hollow bolt rods 7 and 7', which are supported along their length at spaced intervals by concealed guides 9 as will be later described. The ends of the bolt rods are adapted to fit into strikes 9' inserted in the window frame and floor when the two bolt rods 7 and 7' are moved to their projected position by the actuating mechanism. The bolt rods 7 and 7' are hollow being formed from a strip of sheet metal which is bent or stamped to provide a semi-cylindrical wall with spaced bent over edges or flanges forming the bottom face thereof. This construction therefore constitutes a hollow bolt rod having a central longitudinal passageway therethrough communicating with the slot formed between the flanges forming the bottom face of the rod. This feature of the invention is of importance since by providing a hollow rod of this character the guides 9 are entirely concealed from view, as will be later described.

The inner ends 10 and 11 of the hollow rods 7 and 7' are flattened, as is clearly shown in Fig. 9, to provide a solid portion of a double thickness of metal, the flattened portion of the rods being of slightly greater width than the semi-cylindrical portions

thereof. The two thicknesses of the flattened end portions are secured together by means of a headed stud 15 which is secured to a washer 16, the two thicknesses of metal being held between the head of the stud and the washer 16. The flattened end portions 10 and 11 are covered with a casing 17 which is stamped from sheet metal so as to provide a substantial U-shaped piece having a 10 slightly enlarged medial portion 18. This casing is secured to the stile 3 by means of screws 19 which pass through suitable holes in the casing. Two of the screws also pass through the flattened end portions which 15 are provided with elongated slots 20 of sufficient length to permit the bolt rods 7 and 7' to be projected and retracted by an actuating mechanism which will now be described.

The bolt rods 7 and 7' are connected at 20 their inner ends to the curved links 22 and 23 which links are preferably cut or stamped from sheet metal. Each one of these links has a hole or aperture at one end thereof into which the head of the stud 15 fits, the 25 link being freely removable from the stud to permit the parts to be disassembled for the purpose of reversing the direction of rotation of the actuating handle as will be later referred to. The inner or adjacent 30 ends of the two links 22 and 23 are pivoted between two disks 24 and 25 by means of pivot pins 26 which permanently secure the disks and links together. The disks 24 and 25 are substantially circular in shape and 35 are provided with centrally-disposed alining square apertures or holes through which a spindle 27 passes, the spindle projecting beyond the casing 17 and carrying a handle 28 which is secured to the end of the spindle by set screw 29; as is the usual construction. The inner end of the spindle 27 is 40 preferably provided with an enlarged head 30 which prevents inadvertent separation of the spindle from the disks.

The links 22 and 23 are slightly curved 45 as shown in Fig. 2 so as not to interfere with the screws 19 which secure the casing to the stile 3 when the links are in their projected position as shown in this view.

The curvature of the links is also essential 50 to prevent interference with the spindle 27 when the bolt rods are in their retracted position as shown in Fig. 5, since it is obvious that upon rotation of the spindle in 55 a counter-clockwise direction, as is shown in Figs. 2 and 5, the links and disks will be moved from the position shown in Fig. 2 to the position shown in Fig. 5 to thereby retract the bolt rods. The ends 10 and 11 of the bolt 60 rods which slide within the casing 17 are prevented from rattling therein by the enlarged end portions 13 and 14 engaging the side walls of the casing. As will be clear from Fig. 3, the bolt rods themselves do not 65 rest upon the astragals 3, but are spaced

therefrom by the washers 16 which therefore serve to reduce the friction and hence the effort required to operate the bolt rods.

To hold these bolts in their shot or locked position a locking pin 31 may be utilized 70 which is permanently secured to the casing 17 by a flexible chain or cord 32. This locking pin passes through an opening 33 in the casing and through one of the slots 20 in a bolt rod and its end engages in a recess 75 34 provided in the stile or astragal so that when the pin is placed in position its engagement with the end wall of the slot 20 will prevent the bolt from being retracted.

The handle 28 shown in Figs. 1 and 3 is 80 preferably applicable for use with casement windows which open inwardly, that is, with swinging closures where the handle cannot engage the other section of the closure. Where, however, the casement window 85 opens outwardly, the handle 28 should be replaced by a lever handle similar to the lever handle 35 shown in Fig. 10, since if a handle, such as is shown at 28 which is in a crosswise position when the bolt rods 90 are retracted, were utilized with outwardly swinging closures, the end of the handle would engage the other section of the swinging closure unless the handle could be spaced a sufficient distance therefrom which is 95 sometimes impractical with the types of casement windows in common use. Where a lever handle, such as the handle 35, is utilized, to render the construction interchangeable so that the bolt rods may be re- 100 tracted by swinging the lever handle 35 to the left or right, as may be required with different types of swinging closures, the construction described permits the parts to be interchanged without the use of tools and in 105 an entirely simple manner, requiring only that the handle 27 and the casing be removed and the links 22 and 23 slipped off the ends of the studs 15. The spindle is then driven from the plates or disks 24 and 25, the links and disks reversed and the spindle again driven into place; the casing and handle being again assembled as described. The parts will then be in the position shown in Fig. 4, which will permit the 110 bolt rods to be retracted when the handle is rotated in an opposite direction to that shown in Fig. 5.

Referring now to Figs. 6, 7 and 8, one form of a guide which may be used to hold 115 the hollow bolt rods 7 and 7' in position upon the stile or astragal is shown. Each of the guides is stamped from a strip of sheet metal to provide base pieces 40 and 41 which are adapted to rest against the as- 120 tragal or stile 3, and an intermediate body portion 42 which is spaced from the stile or astragal, as is shown in Fig. 6. The guide is secured to the stile or astragal by screws 44 and 45 and to prevent the body portion 125 130

42 from bending it is preferably provided with integral lugs or ears 46 which are formed by cutting U-shaped slots and bending the free portions downwardly. The 5 base pieces 40 and 41 are connected to the body portion 42 by connecting strips 43 which are of less width than the base and body portion to permit the body portion to fit inside of the hollow bolt rods 7 and 7', as 10 is clearly shown in Fig. 8, the body portion therefore serving as a cross head to retain the bolt rod in place through its engagement with the flanges on the hollow bolt. These flanges rest upon the base pieces 40 and 41 15 so as to space the bolt rod from the astragal and to eliminate undue friction. It is obvious that different types of guides may also be employed which have an enlarged portion or cross head corresponding to the 20 body portion 42 to fit within the hollow bolt rods and maintain the same in position.

It is also to be noted that the guide when the Cremorne bolt is in position is concealed from view and has no portions thereof engaging the visible portions of the bolt rods which will permit the bolt rods to be given a high ornamental finish without liability of such finish becoming scratched or marred during the operation of the rod. In this 30 connection it may also be stated that the casing 17 is also out of contact with the portions of the bolt rod which become visible when the bolt rods are projected so as to eliminate any danger of these portions of 35 the bolt rods becoming unsightly by having their finish injured through sliding engagement with the walls of the casing.

The construction shown in Fig. 10 is utilized when it is desired to actuate the Cremorne bolt from both sides of a swinging closure. In this construction the spindle 27' instead of having an enlarged head 30, as in Fig. 3, is extended a sufficient distance beyond the disk 24 to permit a sleeve 48 to 45 be slipped thereover and secured thereto. This sleeve also receives the end of a square spindle 49 which passes through the astra-

gal or stile of the swinging closure to the opposite side thereof where it is secured to the lever handle 35 or other suitable handle, 50 the handle bearing against an escutcheon plate 50 of the usual type. In order to convert the construction shown in Fig. 3 to the one shown in Fig. 10, it is only necessary to replace the spindle 27 by a spindle 27' which 55 may be done without the use of tools, the Cremorne bolt described being therefore capable of universal application to all types of swinging closures with very slight changes of construction, which changes may 60 be effected in an entirely simple manner.

One advantage of the construction which may be referred to is that it is adaptable for use with swinging closures or casement windows having narrow astragals or stiles, 65 since the enlarged portion 18 of the casing is the widest portion of the entire construction.

I claim:

1. In a bolt construction, the combination of a hollow bolt having a longitudinal slot 70 therein and a guide comprising a plate the two opposite ends of which are depressed, the intermediate portion being connected with the depressed ends by narrow necks, 75 said intermediate portion being located inside of the bolt, the depressed ends outside thereof and the necks traversing the slot.

2. In a Cremorne bolt construction, a pair of hollow reciprocating bolt rods each having a slot in the rear face thereof, guide 80 plates wholly hidden behind the rods and having guiding parts projecting through the slots in the bolts, actuating mechanism for the bolts connected to the inner ends thereof, a casing surrounding the actuating 85 mechanism and the adjoining ends of the rods, said casing having inner portions in guiding contact with the rods and other portions equal in length to the movement of the rods extending beyond the guiding portions 90 and which cover but do not touch the rods.

It witness whereof, I subscribe my signature.

OSCAR C. RIXSON.
